UNITED STATES PATENT OFFICE.

MARK VANDERCOOK AND ROBERT T. BUSH, OF GALLATIN, TENNESSEE.

STRAP-CLASP.

SPECIFICATION forming part of Letters Patent No. 376,996, dated January 24, 1888.

Application filed November 29, 1887. Serial No. 256,377. (No model.)

To all whom it may concern:

Be it known that we, MARK VANDERCOOK and ROBERT T. BUSH, citizens of the United States, residing at Gallatin, in the county of Sumner and State of Tennessee, have invented 5 certain new and useful Improvements in Strap-Clasps, of which the following is a specification.

Our invention relates to a metal clasp for 10 uniting harness straps and for attaching buckles to straps.

The invention is illustrated in the accompanying drawings, in which—

Figures 1, 2, and 3 show the clasp applied 15 for the purpose of uniting the ends of two straps. Said figures represent front, edge, and back views, respectively. Fig. 4 is a cross-section view of the clasp uniting the straps. Fig. 5 shows two views of the back plate. Fig. 20 6 shows two views of the front plate. Figs. 7 and 8 show the clasp combined with a strap loop or keeper and applied for attaching a buckle.

The letter A designates the back plate, and 25 B the front plate, of the clasp. The back plate has two openings, e, separated by a central cross-bar, d. The openings form two side bars, e. Each side bar is provided with a flange, e', having two notches, e'', and on its inner face 30 the plate has prongs f to penetrate the leather. The front plate has at each side edge a flange, g, which meets or confronts the flange e' of the back plate, and is provided at each side edge with two tangs, h, each of which is to bend 35 and clinch over the side bar, e, of the back plate, as shown, and occupy the notches e'' thereon. The inner face of the front plate also has prongs f. The front plate, when used for attaching buckles, as shown in Figs. 7 and 8, 40 is provided with a loop or keeper, i, made in-

tegral with it, to confine the free end of a strap j, which is secured in the buckle k. The clasp may have one loop i, as shown, or may have two loops.

It will be seen that the strap ends are 45 clamped securely between the two plates A E and the prongs f penetrate the straps.

The device may be plated or burnished and be made an ornament to the harness.

Having described our invention, we claim 50 and desire to secure by Letters Patent of the United States—

1. A metal clasp for harness-straps, comprising two plates, A B, one of said plates, A, having two side bars, e, each provided with two 55 notches, e'', and also having on its inner face prongs f to penetrate the leather, and the other plate, B, having at each side edge two tangs, h, to bend over the side bars of the opposite plate and occupy the said notches thereon, and 60 also having prongs f, as shown and described.

2. A metal clasp for harness-straps, comprising two plates; A B, one of said plates, A, having two side bars, e, each provided with two 65 notches, e'', and also having on its inner face prongs f to penetrate the leather, and the other plate, B, having at each side edge two tangs, h, to bend over the side bars of the opposite plate and occupy the said notches thereon, and also having prongs f, and provided with a 70 loop, i, integral with the plate, as set forth.

In testimony whereof we affix our signatures in the presence of witnesses.

MARK VANDERCOOK.
ROBERT T. BUSH.
